UNITED STATES PATENT OFFICE.

AUGUST RISCH, OF MILWAUKEE, WISCONSIN.

TELESCOPING ROD FOR CURTAINS.

1,200,027.

Specification of Letters Patent. Patented Oct. 3, 1916.

Application filed November 11, 1915. Serial No. 60,846.

To all whom it may concern:

Be it known that I, AUGUST RISCH, a citizen of the United States, and resident of Milwaukee, in the county of Milwaukee and State of Wisconsin, have invented new and useful Improvements in Telescoping Rods for Curtains, &c., of which the following is a description, reference being had to the accompanying drawings, which are a part of this specification.

The invention relates to telescoping supports.

The invention is designed more particularly to provide a lock for a pair of telescoping rods to prevent inward or shortening movement of said rods with respect to each other and may be used where rods for supporting articles hung over them or from them are employed and is particularly adapted for use as an adjustable curtain rod.

The invention is further designed to provide in addition to the lock above described for the rods, a means for moving the sections outwardly with respect to each other so that when the ends of the rod are placed adjacent two supports and are adjusted to approximate length, this means may be used to move the sections outwardly to bring the ends of the rod firmly against the support and thus secure them in position.

The invention is further designed to provide a curtain rod which may be conveniently disposed between the side frames of a window or may be secured to suitable brackets adjacent the window to secure the curtain in position, the telescoping sections permitting the rod to be used with windows of various widths and to be held in place on the supports without any fastening means except that carried by the rod itself.

The invention further consists in the several features hereinafter set forth and more particularly defined by claims at the conclusion hereof.

In the drawings: Figure 1 is a view of the device embodying the invention, showing it applied to a window as a curtain rod; Fig. 2 is an enlarged view of the device, parts being broken away and parts being shown in section; Fig. 3 is an enlarged view of the device, parts being broken away; Fig. 4 is a sectional view of the device.

The device comprises a pair of telescoping sections or rods 5 and 6, preferably of brass, 55 slidably mounted with respect to each other and forming a support upon which a cur-

tain or other article can be hung, means for securing the rods against inward movement with respect to each other, means at the ends of the rods for engaging a support, and means for moving the rods outwardly so as to bring their ends into firm engagement with said support.

The means for securing the rods against inward movement with respect to each other comprises a sleeve or band 7 loosely and slidably mounted on one of the sections preferably the smaller section 5 and forming a lock. The edge of this sleeve adjacent the end of the larger section 6 is inclined or tapered forming a lip portion 8 and gripping portions 9 and 10. With a construction of this kind when the lip portion 8 is moved into engagement with another member having a beveled end, it will wedge 75 against said member and be lifted upwardly, owing to the loose connection of said sleeve with the rod on which it is mounted, and bring or wedge the portions 9 and 10 into gripping engagement with the 80 rod, as shown in Fig. 4. In the present instance the sleeve 7 is made of hard steel so that it secures a tight grip upon the softer metal brass of which the rod is made. While the end 11 of the rod 6 might be beveled so 85 as to grip the lip 8 of the sleeve 7, I have shown two clamping sleeves 12 and 13 which form in effect a continuation of the rod 6, said sleeves having beveled edges 14, one of which is adapted to engage the lip 8 of the 90 sleeve 7. These sleeves are independently movable with respect to each other and to the rods and form the means hereinafter described for moving the rods outwardly so as to bring their ends into firm engagement 95 with the support to mount the rod thereon.

The means at the ends of the rods for engaging the supports, such as the sides 4 of a window, as shown in Fig. 1, or the sides of supporting brackets consists of end pads 15, 100 preferably of rubber which are secured to end members 16 mounted on the ends of the rods 5 and 6. When the rods have been adjusted to proper length and the sleeve lock set in position, the pads 15 may be brought 105 into frictional engagement with the side supports.

The means for moving the rods 5 and 6 outwardly so as to bring their ends into firm engagement with the side supports comprises the clamping sleeves 12 and 13 having inclined registering abutting edges 17

and 18. These edges form cam surfaces so that movement of one of said sleeves with respect to the other will separate them. Resultantly, as the sleeve lock 7 when once brought up into position against the outer beveled edge 14 of the sleeve 12 will be securely locked to the rod 5, any outward movement of said sleeve 7 will cause an outward movement of the rod 5 and this outward movement of the sleeve 7 will take place when one of the sleeves 12 or 13 is rotated with respect to the other.

The operation of the device is as follows:—The operator first slides the rods 5 and 6 in or out until a length of rod is obtained which will extend across from one side support to the other and bring the ends of the rod sections into engagement with said side supports. Then with the sleeves 12 and 13 in the position, shown in Fig. 2, the sleeve 7 is moved up against the sleeve 12 thereby locking the rod 5 against inward movement. The rod is then put in place between the supports and one of the cam members 12 or 18 is moved with respect to the other causing the spreading of said members and the outward movement of the sleeve 7 and rod 5 as previously described. This outward movement of the rod 5 of course increases the length of the rod and consequently brings the ends thereof into tight engagement with the side supports and in the present instance the rubber pads hold the ends in frictional engagement with the side supports. The spreading or lengthening of the rods obviates the use of any other fastening means than that used to clamp the ends of the rods to the supports. It will be noted that the sleeve, engaging with both the rod 5 and the member 12 which together with the member 13 forms in effect a continuation of the rod 6, has a wedging engagement with said rods which prevents inward movement of the rod 5 with respect to the rod 6.

The invention thus exemplifies a new and improved lock for telescoping rods and

which may be employed on the rods in connection with clamping members to form a curtain rod whose ends clampingly engage the side supports for the rod.

The invention is not to be restricted to the details of construction herein set forth, it being my intention to claim it as broadly as will be permitted by the state of the prior art.

What I claim as my invention is:—

1. The combination, with a pair of telescoping rods, of a lock for preventing inward movement of said rods with respect to each other comprising a sleeve loosely mounted on one of said rods and provided with an inclined surface for wedgingly engaging the other rod, said sleeve also wedgingly engaging the rod on which it is mounted when said rods are moved toward each other.

2. In a curtain rod, the combination, with side supports, of a rod formed of a pair of telescoping sections, a lock for preventing inward movement of said sections with respect to each other, and a pair of clamping members mounted on one of said sections and interposed between said lock and the other section, said members having registering cam surfaces for lengthening said rod by the outward movement of one of said telescoping sections to thereby bring the ends of said sections into clamping engagement with said side supports.

3. The combination of a pair of telescoping rods, a sleeve loosely mounted on one of said rods and having an inclined end disposed adjacent the other rod, said sleeve having wedging engagement with said other rod at one point and having wedging engagement with the rod on which it is mounted at two points to prevent the inward movement of said rods with respect to each other.

In testimony whereof, I affix my signature.

AUGUST RISCH.
